UNITED STATES PATENT OFFICE.

RANSOM F. RANKIN, OF COLUMBUS, OHIO.

HYDROCARBON-BURNER.

SPECIFICATION forming part of Letters Patent No. 268,824, dated December 12, 1882.

Application filed April 29, 1882. (No model.)

To all whom it may concern:

Be it known that I, RANSOM F. RANKIN, of Columbus, in the county of Franklin and State of Ohio, have invented certain new and useful Improvements in Hydrocarbon-Burners; and I do hereby declare that the following is a full, clear, and exact description of the invention, which will enable others skilled in the art to which it appertains to make and use 10 the same, reference being had to the accompanying drawings, which form a part of this specification, and in which—

Figure 1 is a longitudinal central section of my improved hydrocarbon-burner, and Figs. 2 and 3 are perspective views illustrating modifications in the construction of the burner-caps used therewith.

My invention has relation to hydrocarbon-burners, or so-called "vapor-burners," adapted 20 for lighting and heating purposes; and it consists in the improved construction and combination of parts hereinafter more fully described and claimed.

In the accompanying drawings, A represents the wick-tube, the lower end of which is 25 inserted into the lamp-reservoir which contains the naphtha, gasoline, or petroleum, my burner being adapted both to light and heavy oils. This wick-tube fits into another outer 30 tube, B, which may be slid up or down upon the inner tube, A, and has an enlargement, C, of the shape of an inverted cone, with a flat top, C', having one or more fine apertures, c.

Upon the top C' of the enlargement or gas- 35 meter C is placed a hood or cage, D, having a double series of air and draft holes, d and d'. From the point where the wick-tube enters the gasometer it is slotted or perforated, as shown at A' ^{up} to its open top. The top of 40 the outer gas-tube, B, is contracted, as shown at B', leaving a small outlet or opening into another tube, E, which I call the "burner-tube." This is slipped over the top of gas-tube B B', as clearly shown in the drawings, 45 and has air-holes e e at its lower end, and a bridge-piece, F, at its top or mouth, by which fine apertures f f are formed for the escape of the mixed gas and air into the burner-cap G, which has a transverse slit, g, for the flame.

50 I do not confine or limit myself to any particular construction of the burner-cap G, as

that will depend upon the purposes for which the device is to be used; and in Figs. 2 and 3 I have shown burner-caps of different constructions, that represented in Fig. 2 being used when a strong heat is required, as in vapor stoves or heaters, and that shown in Fig. 3 being adapted when a large and spreading flame is required whether for heating or lighting purposes. The burner-cap shown in Fig. 1 will be found useful for illuminating purposes.

Having in the foregoing described the construction of my improved vapor-burner, I shall now proceed to describe briefly its manner of 65 operation.

By heating the outer tube, B, with a burning match or taper sufficient heat will be imparted to the inside wick-tube, A A', to generate gas from the oil held in suspension in the wick, 70 which escapes through the slots or perforations into the gasometer or gas-chamber C and out through its apertures c into the cage D, where the jets of vapor are lighted by the application of a match or taper. Air is fed to 75 the burning jets through the apertures d, and the products of combustion are carried off through the upper openings, d'. The burning jet or jets within the hood or cage D cause a constant vaporization of the oil in the wick-tube, and consequently a constant flow of gas or vapor through the contracted mouth B' of the gas-tube, into which the perforated or slotted end of the open wick-tube is inserted. In 80 burner-tube E this vapor is mixed with air, 85 which enters through the openings e e, the mixed air and vapor escaping through the apertures f f into the burner-cap, and out through its slot or opening g, where it is ignited.

Having thus described my invention, I claim 90 and desire to secure by Letters Patent of the United States—

1. In a vapor-burner, the combination of the inner wick-tube, A, having an upper slotted or perforated part, A', outer gas-tube, B, having 95 the enlargement or gasometer C, provided with one or more perforations in its top plate, C', and contracted mouth B', and cage D, having a double series of top and bottom apertures, d' and d, substantially as shown and set forth. 100

2. In a vapor-burner, the combination of the inner wick-tube, A, having an upper slotted or

perforated part, A', outer gas-tube, B, having the enlargement or gasometer C, provided with one or more perforations in its top plate, C', and contracted mouth B', cage D, having a 5 double series of top and bottom apertures, d' and d, burner-tube E, having air-holes e e, and a suitably-constructed burner-cap, G, substantially as and for the purpose herein shown and specified.

In testimony that I claim the foregoing as my own I have hereunto affixed my signature in presence of two witnesses.

RANSOM F. RANKIN.

Witnesses:

AUGUST PETERSON,
JNO. A. MADIGAN.
